UNITED STATES PATENT OFFICE

EDWARD B. HALL, JR., OF CHICAGO, ILLINOIS, ASSIGNOR TO O-CEDAR CORP'N., OF CHICAGO, ILLINOIS, A CORPORATION OF ILLINOIS

MOP

Application filed September 16, 1931. Serial No. 563,119.

This invention relates to improvements in mops, and more particularly to improvements in mop head construction, the invention being highly desirable both for the construction and manner of connection of handle holding means and swatch holding means, although the invention may have many and various uses and purposes as will be apparent to one skilled in the art.

With mops as previously constructed, certain difficulties have been experienced in the use thereof, one of the chief difficulties lying in the fact that it was almost impossible for an operator or user to acquire easily and readily, as well as maintain, the proper adjustment between the mop handle and the mop head. In many of the formerly known constructions, no adjustment for moving the handle holding member relatively to the mop head was provided, in other instances the handle was movable relatively to the mop head to certain fixed predetermined points, and in still other instances where the handle was movable relatively to the head, the construction was such that in a short time under normal usage the two parts would become relatively loosened and no adjustment at all of any degree of permanency was possible. Furthermore, with mops as heretofore constructed, trouble has ensued in the loosening of the various connections as a direct result of the rough handling to which mops are subjected, it being a common expedient for a user of a mop to pound the same upon a railing to free the mop of dust and dirt. Such abuse tends to loosen engagement of the mop handle and handle holder, in the connection between the handle holder and mop head or swatch holder, and these connections as heretofore made when once loosened remain loosened. Another great objection to mops heretofore known, resided in the fact that not infrequently a user would cause certain parts of the construction of the mop besides the swatch to come forcibly into contact with a surface undergoing cleansing, with resultant injury to the surface.

The present invention has been designed to overcome the above noted, as well as other defects and objections, in the provision of a mop

head construction including a pivotal handle socket easily adjusted into any desired position relative to the mop head, and maintained in this position with a force just sufficient to give the desired degree of permanency.

It is also an object of this invention to provide a mop head construction embodying a pivotal handle socket frictionally held in a position of adjustment by resilient means.

It is also an object of this invention to provide a mop head construction including a pivotal handle socket frictionally held in a position of adjustment with respect to the swatch holder, the friction means being also adjustable to vary the gripping action upon the handle socket member.

A further object of this invention is the provision of a mop head construction including a buffer arranged to contact first with a surface upon which the mop is being used, and thus prevent injurious contact of other portions of the mop head with said surface.

It is still a further object of this invention to provide a mop head construction including a pivotal handle socket, and swatch holding means, wherein the entire device is easily and quickly dismantled and as easily reassembled.

It is a further object of this invention to provide a mop head construction including a handle socket member formed of resilient means whereby the handle socket member is shock absorbing, and said member being equipped with stiffening means in the lower portion thereof to provide the desired rigidity.

Still another object of this invention is the provision in a handle socket member for mops made of wound spring wire, each loop functioning as a thread for engagement with a complementally threaded handle.

While some of the more salient features, characteristics and advantages of a device embodying the present invention have been above pointed out, others will become apparent from the disclosures hereinafter.

The invention includes these and other features of construction and combinations of parts, hereinafter described, and shown in

a preferred form in the drawing, as more particularly indicated by the claims.

On the drawing:

Figure 1 is a fragmentary top plan view 5 of a mop and handle therefor, the mop construction embodying features of the present invention.

Figure 2 is an enlarged fragmentary vertical sectional view of the construction shown 10 in Figure 1 taken substantially as indicated by the line II—II of Figure 1.

Figure 3 is a transverse sectional view 15 taken through the mop head construction as indicated by the line III—III of Figure 2.

Figure 4 is a fragmentary top plan view 20 of the mop head construction immediately adjacent the connection of the handle socket member and the swatch holder.

Figure 5 is a side elevational view of a 25 portion of the connecting means.

As shown on the drawing:

In the illustrated embodiment of this invention, there is shown a swatch holder 10 which may be of any desired character, but 25 which in the present instance is of twisted wire, the threads of a swatch 11 being held securely between the twisted wire. As seen clearly in Figure 1, the swatch holder is generally of an oval shape as indicated by 30 the line 12 and the ends thereof extend inwardly beneath the handle socket where the ends are held joined by means of a through bolt 13 passing through loops 14 formed on the end of the swatch holder. Inclosing each 35 of the loops 14 is a cover plate or cap 15 provided with a relatively short neck portion 16 which acts as a stiffener for the respective ends of the swatch holder adjacent the loop. Each of the cover caps 15 is also 40 provided with a central aperture 17 through which the bolt 13 extends. In this manner the loop on each end of the swatch holder 10 is maintained in proper fixed position and prevented from rotating with respect to 45 the through bolt 13. As will later appear more fully herein, the cover caps 15 are maintained in fixed position over the loop 14 by means of a wing nut 18 engaged on the end of the bolt 13.

50 Of course, handle holding means are provided, and in this instance they include a rigid bar-shaped shank 19 provided with a suitable aperture near one end thereof through which the bolt 13 extends (Fig. 2).

55 On the other end of this shank, a socket 20 is formed, and in this instance the socket is made by closely winding spring wire into a coil. The lower portion of the coil is narrower than the upper portion, and this lower portion is intimately engaged around the shank 19, the coil being preferably welded or otherwise suitably secured to the shank.

60 The upper portion of the socket or coil is expanded to receive the lower end of a mop handle 21. The end of the handle 21 is 65

threaded as indicated at 22, and the spring wire forming the socket is so wound that each turn of the wire functions as a thread complementary to a thread 22, whereby the handle 21 may be readily screwed into engagement with the socket 20. It will be noted that the shank 19 functions as a stiffening means for the lower part of the resilient socket, but terminates short of the lower end of the handle 21 to thereby leave a space between the handle and the shank. Consequently, there will be a somewhat resilient connection between the handle and the mop head, and this resilient connection will absorb shock in the event the mop is pounded over a railing or some similar obstruction to shake dust and dirt therefrom, whereby the threads upon the handle will not become loosened or injured so that a subsequent tight connection can never be established, but in fact the shock will be in most instances be so absorbed that the handle will not even be jarred loose from its initial connection with the socket.

As is apparent in Figure 2, the lower end of the shank 19 projects only a reasonably short distance beyond the bolt 13 in all directions except towards the handle. Disposed one on each side of the shank 19 is a pair of resilient buffers 23, preferably of rubber, and of a sufficient diameter to extend outwardly beyond the end caps 15, the lower end of the shank 19, and the wing nut 18. The buffers 23 are apertured so that the through bolt 13 may pass therethrough, and when the wing nut 18 is tightened, the buffers are held in fixed position by the clamping action of the cover caps 15, as clearly seen in Figure 3. Obviously, the pressure of the buffers upon the shank 19 of the handle holding means may be adjusted to the desired degree by actuation of the wing nut 18. The handle and handle holding means may be readily adjusted to a desired position relative to the swatch holder and will be frictionally held in any position of adjustment by the buffers 23 with any desired degree of permanency. Due to the clamping action of the inner edges of the cover caps 15, the buffers are held against rotation with the shank 19, but the shank 19 under a reasonable force will move between the buffers.

It will also be noted that when polishing some surface, a polished hard wood floor, for example, should the operator exert too much pressure upon the mop handle, the buffers 23 will strike the floor and prevent any other parts of the mop head from marring or otherwise injuring the surface of the floor.

It will also be noted that all of the parts of the handle holding means and mop head are held in assembled relationship by means of the through bolt 13 and wing nut 18, so that in the event it becomes desirable to dismantle the mop for any reason, it is simply

necessary to remove the wing nut 18, pull out the thru bolt 13, and the cover caps 15, loops 14 and the ends of the swatch holder, buffers 23, and shank 19 of the handle holding means, 5 are at once freely removable and replaceable by new parts if occasion warrants.

From the foregoing, it is apparent that I have provided a mop head construction which includes a resilient connection between 10 the handle and mop head, embodies an adjustable friction grip upon a handle holding means whereby a desired adjustment may be made and easily retained with the exact and desired degree of permanency, and also embodies buffer means which prevents any parts 15 of the mop head construction from injuring the surface upon which the mop is used. It is also apparent that the complete construction disclosed and described herein may be 20 easily dismantled and just as easily reassembled. Furthermore, the present invention is exceedingly simple in construction, operation and use, and may be economically manufactured.

25 I am aware that many changes may be made and numerous details of construction may be varied through a wide range without departing from the principles of this invention, and I, therefore, do not purpose limiting 30 the patent granted hereon otherwise than necessitated by the prior art.

I claim as my invention:

35 1. In a mop head, swatch holding means, spaced cover plates for the ends of said means, a bolt passing through said cover plates, resilient buffers between said cover plates and of a size to extend outwardly beyond said cover plates, and a handle holder pivotal on said bolt between said buffers.

40 2. In a mop head, swatch holding means, a handle socket member pivotal relatively to said means, a resilient buffer on each side of said member, inwardly turned end members abutting said buffers, and means for clamping 45 said end members against said buffers to compress the edges of said end members into said buffers to frictionally hold said handle socket member, said buffers projecting beyond the other parts to protect a surface being cleaned.

50 3. In a mop head, swatch holding means terminating in spaced ends, a handle socket member pivotally mounted between said ends, resilient means adjacent said socket member, cover plates over the ends of the swatch holding means and each provided with a neck portion embracing the swatch holding means to stiffen the same, and means for clamping said resilient means against said 55 socket member.

In testimony whereof I have hereunto subscribed my name at Chicago, Cook County, Illinois.

EDWARD B. HALL, Jr.
